[57] CLAIM

The ornamental design for a compartmentalized container for handbags, as shown and described.

DESCRIPTION

FIG. 1 is a front-side perspective view of a first embodiment of the claimed invention;

FIG. 2 is a rear-side perspective view of a first embodiment of the claimed invention;

FIG. 3 is a front elevational view of a first embodiment of the claimed invention;

FIG. 4 is a right-side elevational view of a first embodiment of the claimed invention;

FIG. 5 is a top plan view of a first embodiment of the claimed invention;

FIG. 6 is a left-side elevational view of a first embodiment of the claimed invention;

FIG. 7 is a rear elevational view of a first embodiment of the claimed invention;

FIG. 8 is a bottom plan view of a first embodiment of the claimed invention;

FIG. 9 is a front-side perspective view of a second embodiment of the claimed invention;

FIG. 10 is a rear-side perspective view of a second embodiment of the claimed invention;

FIG. 11 is a front-side perspective view of a third embodiment of the claimed invention; and,

FIG. 12 is a rear-side perspective view of a third embodiment of the claimed invention.
